UNITED STATES PATENT OFFICE.

WILLIAM ROSE, OF GAINSBOROUGH, ENGLAND.

APPARATUS FOR FEEDING WEBS IN CORRECT REGISTER.

Application filed March 1, 1923. Serial No. 622,232.

To all whom it may concern:

Be it known that I, WILLIAM ROSE, a subject of the King of Great Britain, residing at Albion Works, Gainsborough, in the county of Lincoln, England, have invented new and useful Improvements in Apparatus for Feeding Webs in Correct Register, of which the following is a specification.

This invention relates to apparatus for feeding strips, or webs, of paper, or other material, in correct register, relatively to cutting, embossing, or other, devices, and is more especially intended for feeding, from a roll, to a cutting device, a strip of paper, having thereon, at equal distances apart, printed matter, or the like, and, for brevity, we will describe the said invention as so applied, from which its other applications will also be understood, it being generally applicable for feeding strips, or webs, of paper, or other material, in correct register, for all purposes, so that successive portions of the strip, or web, are brought into correct position relatively to its length.

The principal object of this invention is to provide a simple and efficient apparatus whereby the strip, or web, is fed with great accuracy so that any designs, or other matter, which may be printed thereon or otherwise applied thereto, will be successively brought into proper position relatively to the device which is to operate upon the strip, or web.

Presuming, as aforesaid, that a strip of paper with designs, or letterpress, (which we will refer to as printings), printed at equal distances upon it is to be fed to a cutting machine; the said strip has perforations at intervals therein in accordance with the length of the labels, wrappers, sheets, or the like, to be cut therefrom, and in exact and predetermined position relatively to the said printings.

According to this invention the strip is led between a first pair of rotating rollers, then through a retarding device, and afterwards between a second pair of rotating rollers, provided with a device which will engage the said perforations and thereby bring the strip into such position that the said second pair of rollers will feed the said strip in exact position for cutting. The said engaging device preferably consists of a projection, or tooth, on one of the

rollers of the said second pair; a corresponding cavity, or groove, being provided in the other roller of the said second pair, the said projection, or tooth, being so positioned as to engage at the proper times, 60 with the successive perforations in the strip.

Each of the said pairs of rollers will intermittently feed the strip in the direction towards the cutting device, this being 65 effected by portions of the peripheral surfaces of the rollers of each pair, which bear upon the strip between them, there being a gap between these peripheral surfaces so that, during the rotation of the rollers, the 70 operative and inoperative portions thereof are alternately opposed to the strip, the pairs of rollers being so set, relatively to each other, that, during a portion of the time the second pair of rollers is feeding 75 the strip forward, from the aforesaid retarding device, the first pair of rollers is not in operative engagement with the strip, and, alternatively, during a portion of the time the said first pair of rollers is feed- 80 ing the strip towards the said retarding device, the operative surfaces of the second pair of rollers are not in engagement with the strip, but at this particular time, the said tooth, or projection, (which has en- 85 gaged one of the said perforations in the strip) feeds the said strip forward from the said retarding device.

The said retarding device is supported between the first pair of rollers, and the 90 second pair of rollers, in such a position as to cause the strip at this part to be deviated from a plane tangentially disposed relatively to the peripheries of both of the said pairs of rollers. 95

The said retarding device preferably consists of a plate, or block, secured to the frame of the apparatus, and a brake-piece supported in such manner as to press, with but slight pressure, the strip upon the said 100 plate, or block, and prevent the strip advancing at this place unless drawn, or pulled, through the retaining device by the second pair of rollers, or by the projection, or tooth, in connection therewith. 105

We will describe, with reference to the accompanying drawings, the manner in which this invention may be performed premising that we do not limit ourselves to the precise details illustrated. 110

Figure 1 is a plan, of an apparatus constructed in accordance with our invention.

Figure 2 is a side elevation, partly in section and Figures 3 and 4 are longitudinal sections shewing different positions of the first and second pairs of rollers and the intervening retarding device. Figure 5 is a plan of a portion of the strip of paper to be dealt with shewing a convenient relative arrangement of the perforations and printings.

Referring to Figures 1 and 2; 1 represents the framework which supports the various parts of the apparatus.

15 A main driving-spindle 2 is mounted in bearings carried by the framework; the said shaft having, secured to it, a toothed wheel 3, to convey movements of rotation therefrom to the rotatable rollers.

20 The upper roller 4 and a lower roller 5 constitute the first pair of rotatable rollers and the upper roller 6 and a lower roller 7 constitute the second pair of rotatable rollers.

25 The rollers 5 and 7, are secured respectively to the spindles 8 and 10 journalled in bearings carried by the framework.

30 A toothed wheel 11 is secured to one end of the spindle 10 and a similar toothed wheel 12 is secured to the corresponding end of the spindle 8.

35 An intermediate toothed wheel 13 is secured to a short spindle 14 rotatable in a bearing 15 on one side of the framework and retained in position by the collar 16.

40 A spindle 17 is supported by, but is not rotatable in, bosses on the framework and the toothed wheel 18 is rotatably carried on the end of the spindle 17. By means of the gearing described rotative movement is transmitted from the main driving-spindle 2 through the toothed wheels 3, 13 and 11 to the spindle 10 and thence by means of the toothed wheels 18 and 12 to the spindle 8.

45 The upper roller 4 of the first pair of rotating rollers is secured to a spindle 19 which is journalled in bearings 20 and 20^a carried by arms 21 and 21^a pivotally supported at their upper ends upon a spindle 22 carried in bosses 23 on the framework.

50 The upper roller 6 of the second pair of rotating rollers is secured to a spindle 24 which is journalled in bearings 25 and 25^a carried by arms 26 and 26^a pivotally supported at their upper ends upon the aforesaid spindle 22. Lugs 27 and 27^a, extend upwards respectively from the arms 21 and 21^a and similar lugs, 28 and 28^a, extend from the arms 26 and 26^a—the lugs 27 coming opposite the lug 28 and the lug 27^a coming opposite the lug 28^a and a spring 29 being placed between each pair of lugs so opposed and acting to retain the upper rollers 4 and 6 in contact with the strip as it passes between the said pairs of rollers.

The ends of the spindles of the rollers 19 and 24 have secured to them toothed pinions marked respectively 30 and 31 which engage like pinions secured to the spindles of the lower rollers 5 and 7 respectively. 70

Only a portion 32 of the upper roller 4 of the first pair of rollers is adapted to bear upon the strip of paper 33 so that during their rotation the rollers of this pair are alternately operative and inoperative upon 75 the strip.

The lower roller 7 of the second pair of rollers has a portion 32 of its periphery removed and is provided with a projection or tooth 34, a corresponding cavity 35 being provided in the periphery of the upper roller 6 of the said second pair of rollers. The projection or tooth 34 is so situated as to engage at the proper times with the perforations 42 in the strip 33, which perforations are arranged at equally spaced distances along the said strip and in definite positions relatively to each design or set of designs, or printings, 43 on the said strip. 80

85 A block 36, shaped as shewn in Figure 2, and provided with a flange 37 at each side, is secured to the spindle 17 in such position that the upper portion 38 of the said block causes a strip 33 to be tangentially disposed relatively to the peripheries of the 90 first and second pairs of rollers.

95 The aforesaid retarding device comprises a brake-piece 39 the ends, or trunnions, of which engage slots 40 in the flanges 37. The said brake piece pressing, with but slight pressure, the strip 33 against a portion 41 of the block 36 thereby preventing the strip 33 advancing at this place unless drawn, or pulled, by the second pair of rollers, or by the projection, or tooth 34 thereof. 100

105 A plate, or shelf, 44 (Figure 2) is supported between the second pair of rollers and the cutting, or other, device employed 110 and beneath the strip 33 as it passes between the said rollers and device, which device may be of any suitable kind.

110 The said cutting device illustrated is constructed as follows:—

115 Secured to the main driving spindle 2 is a roller 45. A strip 46 of wood, fibre, or other suitable material is secured in a longitudinal recess in the said roller. A spindle 47 is rotatably supported at its ends in bearings 48 carried by the framing. A roller 49 is secured to the spindle 47 and a longitudinal cutter 50 is secured by wedging, or other suitable means, to the roller 49 and is adapted to cut transversely through the 120 strip 33 as the said roller 49 rotates. A toother pinion 51 secured to the spindle 47 engages with a corresponding toothed pinion which is secured to the main driving spindle 2. 125

130 In the example of construction we have

illustrated the relative proportions of the several toothed wheels and pinions are such that at each rotation of the main driving spindle 2 the rollers of the first and second pairs make one revolution, and the cutting device is operated to sever one sheet from the strip 33.

The dimensions of the operative surface, or surfaces, of the first pair of rollers 4 and 5 are such as to ensure that the rollers intermittently feed the web forward to the block 36 and coacting brake piece 39 at a speed slightly in excess of the speed at which the web is drawn from the block and brake piece. The dimensions of the operative surfaces of the second pair of rollers 6 and 7 and the position of the said surfaces relatively to the projection, or tooth, 34, are such as to ensure that each of the perforations 42 in the strip 33, whilst the said operative surfaces are in engagement with the said strip, will in turn, by the rotation of the said second pair of rollers, be brought into such position that the projection, or tooth, 34, will readily engage with one of the perforations 42.

When the apparatus is in action the first pair of rollers 4 and 5 feeds the strip 33 towards the brake-piece 39 which temporarily arrests forward movement of the said strip 33, so that a portion thereof assumes an arched shape (as seen in Figure 2) and accumulates between the said first pair of rollers 4 and 5 and the retarding device constituted by the portion 41 of the block 36, and the brake-piece 39 this accumulation or arching being ensured by the upper portion 38 of the block 36 being so situated as to deviate the strip 33 from a plane tangentially disposed relatively to the peripheries of the rollers 4 and 5, that is, to take a course longer than a straight line between the rollers 4 and 5 and the retaining device 39-41.

The pressure which the brake-piece 39 exerts upon the strip 33 is so slight that whilst the first pair of rollers 4 and 5 is feeding the strip 33 forwards towards the brake-piece 39 the projection, or tooth 34 on the lower roller 7 of the second pair of rollers will pull, or draw, the strip 33 to the necessary extent without tearing, at the perforation 42, or otherwise injuring the strip which may therefore be of thin or tissue paper of but little strength.

Whilst the second pair of rollers 6 and 7 is inoperative upon the said strip the projection, or tooth 34, by engagement with the forward end of one of the perforations 42, moves the strip so that one of the printings 43 is brought into proper and exact position relatively to the operative portions of the peripheries of the second pair of rollers. By the continued rotation of the said rollers the strip is fed forward in correct

position relatively to the cutting device, whilst the projection, or tooth, 34 passes out of engagement with the perforation 42.

For a portion of the time during which the strip 33 is being drawn, or pulled through the retarding device, by the second pair of rollers, the first pair of rollers does not engage the strip, because the inoperative surfaces of the said rollers are presented thereto and the accumulated, or arched, portion of the strip, between the said rollers and the retarding device, is easily drawn, or pulled, through the said retarding device.

Immediately before the operative surfaces of the second pair of rollers leave the strip 80 the operative surfaces, of the first pair of rollers, again engage the strip and feed it towards the retarding device.

As the aforesaid operations are repeated, the strip is, at each operation, fed the required definite extent towards the cutting device, and will be cut at the exact places required to separate the strip into the requisite lengths with the printings in proper position thereon.

We do not limit ourselves to the precise details hereinbefore described and illustrated in the accompanying drawings as modifications may be made without departing from the nature of this invention; for example, instead of there being but one perforation for each length into which the strip, or web, is to be cut there may be two, or more, perforations and a corresponding number of projections, or teeth, and recesses be provided on, and in, the rollers of the second pair.

What I claim is:—

1. In apparatus for feeding webs in correct register, the combination of two pairs of rotatable rollers and a retarding device between said pairs of rollers, in which the retarding device consists of a plate secured to the frame-work and a brake-piece adapted to temporarily arrest the forward movement of the part of the web fed towards the said retarding device by the first pair of rollers by pressing slightly upon the web until it is drawn through the said retarding device, as hereinbefore explained.

2. In apparatus for feeding webs in correct register, the combination of two pairs of rotatable rollers and a retarding device between said pairs of rollers, in which a portion of the retarding device is so shaped and arranged that the part of the web between the first pair of rollers and the retarding device is caused to properly deviate from a plane tangentially disposed relatively to the peripheries of the two pairs of rollers; as and for the purpose described.

In testimony whereof I have signed my name to this specification.

WILLIAM ROSE. .
